(57) **CLAIM**

The ornamental design for a sleeve for glass vessel, substantially as shown.

DESCRIPTION

FIG. 1 is a perspective view of a sleeve for a glass vessel, according to a first embodiment;

FIG. 2 is a front view of the sleeve for a glass vessel, according to the first embodiment;

FIG. 3 is a rear view of the sleeve for a glass vessel, according to the first embodiment;

FIG. 4 is a right side view of the sleeve for a glass vessel, according to the first embodiment;

FIG. 5 is a left side view of the sleeve for a glass vessel, according to the first embodiment;

FIG. 6 is a top view of the sleeve for a glass vessel, according to the first embodiment;

FIG. 7 is a bottom view of the sleeve for a glass vessel, according to the first embodiment;

FIG. 8 is a perspective view of a sleeve for a glass vessel, according to a second embodiment;

FIG. 9 is a front view of the sleeve for a glass vessel, according to the second embodiment;

FIG. 10 is a rear view of the sleeve for a glass vessel, according to the second embodiment;

FIG. 11 is a right side view of the sleeve for a glass vessel, according to the second embodiment;

FIG. 12 is a left side view of the sleeve for a glass vessel, according to the second embodiment;

FIG. 13 is a top view of the sleeve for a glass vessel, according to the second embodiment; and,

FIG. 14 is a bottom view of the sleeve for a glass vessel, according to the second embodiment.

The sleeve material is an opaque or translucent, pliable polymer material. The broken line elements in all views are for illustrative and environmental purposes only and form no part of the claimed design.

1 Claim, 9 Drawing Sheets
